WEIGHT CARRYING CONVEYER FOR
FOUNDRIES

Harrison E. Fellows and Maurice O. Holtan, Milwaukee, Wis.; said Holtan assignor to said Fellows

Application May 14, 1948, Serial No. 27,038

7 Claims. (Cl. 22—20)

1

This invention relates to weight and mold handling apparatus for foundries.

It is a primary object of the invention to render as nearly automatic as possible the transportation and handling of molds and the weights which are superimposed thereon to hold the cope to the drag during pouring. More specifically, it is the object of the invention to provide a construction in which the several molds are moved on to rotatably adjustable carriers on a conveyor system and moved from point to point and turned from side to side as required, the weights being lifted by a separate conveyor system to position on the copes, deposited there, and removed by the same conveyor system at another point in the travel of the mold.

The specific construction of the conveyors and carriages and weight handling apparatus and the organization of the several parts with regard to each other and to the work to be handled are important features of the invention as will hereinafter more fully appear from the following disclosure thereof.

In the drawings:

Fig. 1 is a diagrammatic plan view of apparatus embodying the invention, the relative positions of the mold carriers and weights being diagrammatically illustrated thereon.

Fig. 2 is a view taken in cross section through the apparatus in the plane indicated at 2—2 in Fig. 1.

Fig. 3 is a view of portions of the apparatus in section and other portions in side elevation in the plane indicated at 3—3 in Fig. 2.

Fig. 4 is a fragmentary detail view in perspective of one of the weights and a portion of the apparatus for the handling thereof.

Fig. 5 is a fragmentary detail view in side elevation of one of the carriers as it appears from the point indicated on the line 5—5 of Fig. 1.

Fig. 6 is an enlarged detail view in side elevation of one of the carriers.

Fig. 7 is an enlarged detail view in front elevation of one of the carriers.

Fig. 8 is a still further enlarged detail view in transverse section on the line 8—8 of Fig. 9.

Fig. 9 is a fragmentary detail view of a portion of one of the conveyors including a fragment of one of the carriers suspended therefrom, and also showing an indexing cam.

Fig. 10 is a detail view taken in section on the line indicated at 10—10 in Fig. 9.

My apparatus comprises an elongated mold handling conveyor 15 and a relatively short weight handling conveyor 16. Each comprises

2

an overhead track 17 (Figs. 8 and 9) beneath which operates an endless chain 18 composed of mutually pivoted links 19, 20 and special links at 21 for the load carrying portions of the chain, these latter links also supporting the chain itself from the overhead track by means of arms 22 carrying wheels 23 operating on the track 17.

In the case of the weight handling conveyor 16, the chain indicated by dotted lines in Fig. 1, 10 passes around but two sprockets 24, 25, either of which may comprise the driver. In the case of the much longer mold handling chain 15, which pursues quite a devious path, the chain passes around the sprockets 26, 27, 28, 29, 30, 31, 15 32, 33 and 34, any one of which may be the driver.

The general organization of the apparatus may best be understood from the diagrammatic illustration of Fig. 1 before the details of the mechanism are described.

20 In Fig. 1, the small rectangles shown at 50 in significant locations represent the carriers. At the loading zone A these are aligned with the conveyor track to receive molds which are represented by the small rectangles 36 and are loaded 25 on to the carriers from the roller type conveyor 37.

At A', as indicated by the symbols in Fig. 1, the carriers and the superposed molds are indexed 90° in the course of their advance along the conveyor to position the molds to receive the weights which are loaded thereon as a preliminary to pouring.

At the weighting station B, weights represented by the small rectangles 38 are added to 35 the molds 36. These pass with the molds to the turning station C where the carrier is reversed in position, and to the pouring station D where molten iron is poured into the molds. Throughout the track of conveyor 15 beyond the pouring 40 station is the setting zone E. Ultimately, the carriers pass through another turning zone F to the unweighting zone G, beyond which they are again turned in the turning zone H. Cooling continues through the cooling zone I and the dumping of the mold and casting are finally 45 effected at J. The carrier is finally restored to its original position in the turning zone K to receive a newly delivered mold to be loaded thereon at station A as above described.

50 For details of the carrier, reference is now made to Figs. 6 to 10.

Suspended from the special links 21, which are substituted in spaced pairs for links 20 in the conveyor chain, are the suspension bars 40 (Fig. 9) which support a bridge comprising spaced

angles 41. Depending from this is a pivot shaft 42 supported on cross bolt 43. A nut 44 at the lower end of the pivot shaft supports a cam 45 (Fig. 8) which has a convoluted upper surface engaged by the complementary cam 46 on the under side of the carrier frame 50. As clearly appears from Fig. 6, the carrier frame is C-shaped in side elevation. It comprises a top member 51, a bottom member 52 and a laterally offset single side member 53, the latter being braced by gussets 54, 55 from the top and bottom members to make a rigid carrier. The entire carrier is rotatable about the vertical axis of the suspending pintle shaft 42, but the complementary convoluted surfaces of the cams 45, 46 resist rotation from indexed positions which are 90° apart, there being four convolutions in each cam. In any one of these positions, the carrier tends to remain non-rotatable but by the application of a sufficient rotating force, the carrier will be raised slightly upon the respective cams 45, 46 and caused to index 90° to the next successive position.

Mounted on the bottom member 52 of the carrier 50 is a tiltable sub-frame 56 (Figs. 5, 6 and 7). The sub-frame is pivoted on pintles 58 sufficiently toward the outside of the carrier so that the sub-frame normally is perfectly stable. Mounted on the tiltable sub-frame are a number of rollers 59 comprising a short conveyor assembly for facilitating the movement of pallet-supported molds on to the sub-frame. To preclude the pallets from moving too rapidly across the rollers 59, I may apply a short piece of sheet metal at 60 (Figs. 5, 6 and 7) across two of the rollers to act as a friction brake. As the pallet 61 rides on to these rollers in the manner shown in Figs. 5 and 7, a portion thereof may rest upon the brake strap 60 to assist in bringing the pallet to rest at the desired central point on the carrier. Also provided is an upstanding finger at 63 which engages within one of the pallet runners to hold the pallet on the conveyor when the mold and casting are dumped at the unloading station J, this being accomplished by a pneumatic jack having a cylinder 64, plunger 65 and a roller 66 operating against the lower surface 67 at the rear of the sub-frame. When this cylinder is supplied with air through the hose 68, the entire sub-frame 56 pivots on the pintles 58 thereby dumping the mold and casting at station J but retaining the pallet 61 for later removal.

Disposed on the top member 51 of the carrier 50 is a frame 70 which provides striker arms 71 which project laterally at 90° intervals around the axis of the rotation of the carrier on its suspending rod 42 (see Figs. 9 and 10). In the path of successive arms 71, as the carrier moves with the conveyor chain, are the rollers 72 suspended from overhead by brackets 73 and located wherever indexing movement of the carrier is desired. In the device as shown, the indexing movement always occurs in the same direction and its angular extent is 90° in each operation. Thus, at A' in Fig. 1, the indexing movement is counter-clockwise and involves a single operation. However, at station C, where it is necessary to index the carrier 180°, this is done in two successive counterclockwise operations as indicated diagrammatically in the drawing. The same is true at F and H. It will be apparent from Fig. 10 that the design is such that each successive arm 71, in clearing the roller 72, will tend to move exactly 90°. The complementary cam members

45 and 46 coaxial with the supporting pivoted rod 42 on which each carrier oscillates assure the accuracy of the angular movement.

The conveyor 16 is located at a lower level as is clearly shown in Fig. 2. Its track 170 is identical with the track 17 of conveyor 15 with the exception that it has at stations B and G inclined portions 75 (Fig. 3). Fig. 3 happens to show station G but a view of station B would present a counterpart.

The chain and its suspending arm and rollers are the same in this conveyor as in the main conveyor. However, the carriers 76 comprise merely bars which hang downwardly from the 15 chain and are provided at their lower ends with a cross rod 77 (Fig. 4) which constitutes oppositely extending arms with free ends.

Each of the weights 38 has a pair of spaced brackets 78 which extend upwardly from one 20 side thereof and across the center to points above the longitudinal center of balance. Here each of the brackets 78 carries an inverted channel 79 with upwardly converging sides in which the rod 77 of the suspending bar 76 is freely movable to 25 and from engagement. The arrangement is such that there is plenty of clearance beneath the channel 79 for the hanger 77 to move to and from position when disengaged from the channels. Thus the hangers are enabled to pick up 30 and deposit the weights entirely automatically.

Referring to Figs. 1, 2 and 3, it will be observed that Fig. 3 shows the parts as they appear at station G at which a casting has already been poured and is cooling in the mold 36. The mold, 35 comprising drag 360, cope 361 and jacket 362 is resting on the conveyor section 59 of the sub-frame 56 of the carrier 50. The weight 38 has been superimposed on the cope throughout the pouring operation. It is now desired to remove 40 this weight. Accordingly, carrier 76 of the secondary conveyor 16 has just arrived around the pulley 25 and the proximity of the two conveyors at station G has brought the rod 77 directly beneath the receiving channels 79 on the weight brackets 78.

As the mold carrier 50 and the weight carrier 76 move in unison from right to left as viewed in Fig. 3, the inclined portion 75 of the track 170 of conveyor 16 is reached, whereupon the rod 77 moves up into engagement with the channels 79 as shown in the intermediate position in Fig. 3. With continued movement of the conveyors from right to left, a further lifting of the carrier 76 will ensue, whereby the weight 38 will be lifted 55 clear of the cope 361 and returned around the sprocket 24 to be replaced upon another mold at station B. The replacing operation is simply the converse of that illustrated in Fig. 3, the weight being lowered on to the cope, the continued downward movement of the carrier 76 freeing its rod 77 from the channel 79 and the rod being thereupon withdrawn by passage of the conveyor around the sprocket 25 in one direction, while the mold conveyor passes in an opposite direction around the sprocket 26.

Where a variety of different molds are being poured at the same time, and different sizes of weights are required, it is only necessary to substitute different carrier links 76 to compensate 70 for any changes in height of the respective weights. In such cases, assuming that there are ten carrier links on the secondary conveyor 16, we arrange our molds in sequence corresponding to the sequence of the links so that every time a 75 given link brings a weight of a given size to the

weighting station B, the mold receiving the weight at such station will be the proper mold for that weight. This means that the weight must have been removed in properly timed sequence from the unloading station G, a synchronism readily achieved if the molds repeat themselves with the same frequency as there are carriers on the secondary conveyor.

A device made in accordance with the present disclosure will function entirely automatically, requiring neither manual effort nor even guidance to place and remove the weights or to effect the indexing of the carriers. The operation may be briefly reviewed:

The molds, each comprising a cope, drag and jacket, arrive, fully assembled on conveyor 37. At station A the short roller conveyor section with which each of the carriers 50 is provided, registers momentarily with conveyor 37 and the assembled mold is rolled on to the carrier. At station A', the carrier indexes 90° to a position for receiving the weight 38 which is transported to it by secondary conveyor 16 from another carrier which has been unloaded at station G. At station B, the weight is placed on the new mold automatically through the relative change of heights resulting from the movement of the secondary conveyor respecting its inclined track as above described. Thereupon the carrier of the secondary conveyor moves, without any weight, around sprocket 16 while the loaded carrier 50 moves around sprocket 26 to station C where it experiences two successive indexing movements, causing it to face in the opposite direction with respect to its conveyor. This faces the mold outwardly to receive the molten metal at the pouring station. After pouring, the metal is given time to set and then, at F, two successive indexing operations occur which again face the carrier inwardly for weight removal, which occurs at station G. The empty carrier 76 of the secondary conveyor swings around the sprocket 16 with its lifting rod 77 at a considerably lower level than the receiving channel 79 of the weight. After the parts have registered as shown at the right in Fig. 3, the inclined track lifts the carrier thereby picking the weight from the mold and swinging it around the sprocket 24 for reuse on another mold. Meantime, the empty mold is again subjected to a double indexing adjustment at station H and thereupon continues to cool until it is finally dumped at station J.

We claim:

1. A device of the character described comprising a mold conveyor and a weight transferring conveyor, the said conveyors having two parallel portions to and from which said conveyors laterally converge and diverge, mold carriers suspended from the mold conveyor and provided with swiveled connections therewith for carrier indexing movement, the respective carriers having laterally accessible loading surfaces, and a plurality of indexing means for unidirectionally indexing the laterally open surface to various positions respecting the mold conveyor, said indexing means including a first indexing device for indexing the carrier to render its surface accessible outwardly to receive a mold, a second indexing device for rotating said carrier to render such surface accessible inwardly to receive from said weighting conveyor a weight on said mold, said weighting conveyor having a pick-up rod for alignment and for movement out of alignment with a weight in converging and diverging movement of said conveyors, the weighting conveyor 75 ferring conveyor comprising weight carriers

comprising weight lifting carriers and a weight each freely disengageable from its respective carrier upon relative vertical movement therebetween, the weighting conveyor including a track having an inclined portion for effecting such movement.

2. In a device of the character described, the combination with a mold handling conveyor and a weight handling conveyor, the two conveyors having a plurality of parallel runs, of mold carriers movable with the mold handling conveyor, weight carriers movable with the weight handling conveyor, the two conveyors being provided with means for their operation in synchronism, and weights having vertically engageable and disengageable hooks for detachable connection with the respective weight carriers, one of the parallel runs at each point where said runs are parallel being provided with means for effecting relative vertical movement between said carriers for the transfer of a weight from one to the other.

3. The device of claim 2 in which the means for effecting relative vertical movement comprises an inclined track with which one of the conveyors is provided.

4. The device of claim 2 in which each weight has a pair of spaced brackets extending upwardly from one of its sides and overhanging toward the center thereof and provided with longitudinally spaced downwardly opening channel-shaped hooks, the weight conveyor having oppositely projecting arms engageable in the respective hooks.

5. In a device of the character described, the combination with a weight transfer conveyor comprising an overhead track, a chain circuitously following the track rollers mounted on the track and supporting the chain, and sprockets over which the chain operates, the track being endless, weight suspension members depending from said chain and supported by said rollers, oppositely projecting arms on said members, weights having overhanging brackets provided with hooks engageable with said arms at opposite sides of said members, and a mold handling conveyor having a circuitous path including two runs contiguous to portions of the weight handling conveyor, mold carriers movable along the mold handling conveyor, the weight handling conveyor being directly beneath the mold handling conveyor at said runs, and said carriers being vertically elongated and having lateral openings sufficient to accommodate the weight handling conveyor, together with means for effecting relative vertical movement between the mold handling conveyor and the said arms for vertically adjusting the weight onto and away from a mold on the mold handling conveyor.

6. In a device of the character described, the combination with a mold handling conveyor comprising an overhead track, a conveyor chain movable along the track, and a plurality of carriers swiveled to said chain for indexing suspension therefrom, each of said carriers having a top and a bottom and being open at its side, the bottom comprising a mold support exposed at the open side of the carrier, together with a weight transferring conveyor mounted to move in a path convergent upon and then divergent from the mold handling conveyor and having a portion disposed directly beneath the track of the mold conveyor, said weight transferring conveyor lying within the open sides of successive carriers moving along the track of the mold conveyor, the weight transferring conveyor comprising weight carriers

adapted to transfer a load onto and away from the carriers of the conveyor first mentioned, weight means for such transfer being provided with interengageable surfaces laterally open for interengagement with the weight transferring conveyor in the converging movement of said conveyors.

7. The device of claim 6 in further combination with a weight detachably hooked to a weight carrier, and means for effecting relative vertical movement of the weight carrier with respect to a mold carrier within the open side thereof to an extent sufficient to transfer said weight from one of said carriers to the other.
